UNITED STATES PATENT OFFICE.

ARTHUR H. SCOTT, OF PHILADELPHIA, PENNSYLVANIA.

CABINET FOR DISPENSING TOILET-PAPER.

No. 863,662.

Specification of Letters Patent.

Patented Aug. 20, 1907.

Application filed January 24, 1907. Serial No. 353,851.

To all whom it may concern:

Be it known that I, ARTHUR H. SCOTT, of the city and county of Philadelphia, State of Pennsylvania, have invented an Improvement in Cabinets for Dispensing 5 Toilet-Paper, of which the following is a specification.

My invention has reference to cabinets for dispensing toilet paper and consists of certain improvements which are fully set forth in the following specification and shown in the accompanying drawings which form a part 10 thereof.

The object of my invention is to provide an effective means for containing and dispensing toilet paper from flat packets and which shall restrict the discharge to single sheets and prevent surreptitious removal of the 15 packet from the cabinet.

My invention consists of a stationary frame adapted to support the packet of paper, combined with a front sectional or jointed cover for shielding the packet and pivoted to the stationary frame, and a discharging roller 20 shielded by the lower section of the cover and adapted to act upon the paper packet to intermittently discharge the sheets thereof.

My invention may be so constructed that the discharging roller may be carried by the lower movable 25 section of the cover or by the main or stationary frame as preferred.

My invention also comprehends details of construction which, together with the features above set forth, will be better understood by reference to the drawings, 30 in which:

Figure 1 is a side elevation of my improved cabinet; Fig. 2 is a front elevation of the same with a portion broken away; Fig. 3 is a sectional side elevation on line 3—3 of Fig. 2; Fig. 4 is a front elevation, with part 35 in section, of another form of my invention; Fig. 5 is a side elevation of the same; and Fig. 6 is a sectional elevation of the same on line 6—6 of Fig. 4.

A is the stationary frame and is adapted to be secured to the wall or partition. This frame is preferably provided with an oblique face B upon which the paper packet J rests and also is provided with an upright support I upon which the paper packet is suspended, said packet preferably having a pocket at its upper rear portion of the usual form.

E is a roller having the portions E' of large diameter which rest directly in contact with the paper for the purpose of creating a frictional contact therewith in the act of detaching the sheets successively when the roller is rotated.

The cover consists of two parts, C and C', hinged together and jointed to the stationary frame, and said parts are provided with means for locking them in closed position.

Referring to Figs. 1, 2 and 3, the roller E is journaled 55 in the lower section C' of the cover, which cover con-

sists of the parts C and C' hinged together at D'. The upper section C is hinged to the stationary frame A at D and is adapted to shut down tight, whereas the lower section C', which carries the roller E, is so hinged to the upper section that it may be swung in toward the stationary part A and thus cause the roller to continually press upon the paper J. The section C' overlaps the part C so that when it swings inward there will be no gap or opening between the two sections. The weight of the section C' and its roller E causes the latter to 65 press upon the paper with considerable friction, amply sufficient to disengage the sheets when the roller is rotated. To lock the upper section C of the cover in closed position, I may employ a hooked part R on the lower section C' which engages with a pin T on the stationary part when said lower section is lowered to bring the roller E to rest upon the paper. The under part of the section C' of the cover is open as at K to permit the passage of the paper sheets under the action of the discharging roller E. The roller E is prevented from rotating backward by means of the pawl f hinged to the cover section and engaging the ratchet wheel F on one end of the roller. The end of the roller is provided with a lateral extension terminating in a knob e by which to rotate it. The lower section C' of the cover is 70 locked against being opened by a pawl G' on said cover engaging a rack G on the stationary part A. As the cover advances upon the removal of the paper and continues to exert its weight as a means of creating a friction between the roller and paper, the pawl G' successively 75 engages the teeth of the rack and prevents retraction on the part of said cover. In this manner, the cabinet is locked against theft of the paper packet. By means of the lock H the pawl G' may be disengaged from the rack G when it is desired to insert a fresh packet of 80 paper.

In the construction shown in Figs. 4, 5, and 6, I have arranged both parts C and C' of the cover to be hinged together and to the main frame A at D, and the upper section C is locked in closed position by a hooked pawl 95 G² engaging a ratchet tooth G on the stationary frame A. A key lock H may be employed, as before, to operate the pawl G² to unlock the cover when the cabinet is to be replenished with more paper. The lower part C' of the cover is free to swing inward and presses by its 100 weight upon the paper packet as shown in Fig. 6. In this manner the paper packet is held against the oblique surface B of the stationary frame. The roller E E' in this case is journaled in the stationary frame back of the paper and operated through slots b in the face B as 105 shown. The roller is operated by the knob e and gears e', the latter being to secure a backward rotation of the roller for the natural forward rotation of the knob e. A slot c is provided in the part C' of the cover to permit it to pass the shaft of the knob in advancing the paper 110

upon the roller. Either of these types of my invention may be employed, but I prefer that shown in Figs. 4, 5 and 6 as being most suitable in commercial use.

It is evident that the general shape of the cabinet may 5 be varied, as may also the details, without departing from the spirit of the invention.

Having now described my invention, what I claim as new and desire to secure by Letters Patent, is:

1. In a cabinet for dispensing toilet paper, the combination 10 of a stationary frame upon which the packet of paper is supported, a sectional cover hinged to the stationary frame and having its lower section movable to or from the stationary frame, and a feeding roller for discharging the sheets from the packet carried by the stationary frame and shielded by the lower section of the cover and adapted to be operated by a laterally extending handle.

2. In a cabinet for dispensing toilet paper, the combination 20 of a stationary frame upon which the packet of paper is supported, a sectional cover hinged to the stationary frame and having its lower section movable to or from the stationary frame, a locking device for preventing the cover being opened, and a feeding roller for discharging the sheets from the packet.

3. In a cabinet for dispensing toilet paper, the combination 25 of a stationary frame upon which the paper packet is supported, a sectional cover extending over the front of the stationary frame having its upper section locked to the stationary frame and its lower section adapted by gravity to move or swing toward said frame, and a feeding roller carried in the stationary frame the lower section of the cover being adapted to be forced toward the stationary frame by gravity action to create a friction by the roller upon the paper packet.

4. In a cabinet for dispensing toilet paper, the combination 35 of a stationary frame upon which the paper packet is supported, a sectional cover extending over the front of the stationary frame having its upper section locked to the stationary frame and its lower section adapted by gravity to move or swing toward said frame, a feeding roller to operate upon the paper packet and shielded by the cover, and means for permitting the lower section of the cover to move toward the fixed frame but hold it against movement in the opposite direction.

5. In a cabinet for dispensing toilet paper, the combination 45 of a stationary frame upon which the paper packet is supported, a cover comprising an upper part hinged to the stationary frame so as to extend over the upper portion of the paper packet and a lower part hinged relatively to the upper part and adapted to extend over the lower

portion of the paper packet, a feeding roller for creating 50 a friction upon the paper packet for disengaging the sheets thereof, and means to lock the cover in position upon the stationary frame.

6. In a cabinet for dispensing toilet paper, the combination 55 of a stationary frame upon which the paper packet is supported, a cover comprising an upper part hinged to the stationary frame so as to extend over the upper portion of the paper packet and a lower part hinged relatively to the upper part and adapted to extend over the lower portion of the paper packet, a feeding roller for creating a 60 friction upon the paper packet for disengaging the sheets thereof, and means to lock the upper part of the cover rigidly in position upon the stationary frame while permitting freedom of movement of the lower part of the cover toward the stationary frame.

7. In a cabinet for dispensing toilet paper, a stationary 70 frame, combined with means for supporting the paper packet thereon, a roller carried by the stationary frame for discharging the sheets successively, a cover comprising upper and lower parts adapted to shield the packet movable with respect to the stationary frame, one part of said cover being provided with means for locking it to the stationary frame.

8. In a cabinet for dispensing toilet paper, a stationary 75 frame, combined with means for supporting the paper packet thereon, a roller carried by the stationary frame for discharging the sheets successively, a cover comprising upper and lower parts adapted to shield the packet movable with respect to the stationary frame, the upper part of said cover being provided with means for locking it to 80 the stationary frame and the lower part being free to swing toward the roller and adapted to press upon the paper packet.

9. In a cabinet for dispensing toilet paper, a stationary 85 frame, combined with means for supporting the paper packet thereon, a roller carried by the stationary frame for discharging the sheets successively, a cover comprising upper and lower parts adapted to shield the packet movable with respect to the stationary frame, both parts of said cover being pivoted and the upper part being provided with means for locking it to the stationary frame and restricting the movement of the lower part away from the roller.

In testimony of which invention, I have hereunto set my hand.

ARTHUR H. SCOTT.
